3 Claims. (Cl. 171—252)

The present invention relates to the members of a magneto electric ignition apparatus which conduct the magnetic flux through the ignition coil. The star shaped members used up to now for transmitting the flux through the ignition coil have conical holes fitting the conical ends of the coil core. This design is not satisfactory as it is difficult to get an intimate fit between the star shaped conducting members and the conical ends of the coil core. In some places an air gap remains between the conical hole of this conducting member and the ends of the coil core affecting the path of the flux from that member to the core and thereby reducing the efficiency of the apparatus.

The object of this invention consists in that the arms of said flux conducting members which arms are at right angles to the axis of the ignition coil are turned out cylindrically and firmly pressed against the cylindric ends of the coil core, and that in another constructional form these conducting members are made longer than usual and have such a shape that they form at the same time the coil core itself. These conducting members are laminated. The core portion of each sheet of one conducting piece is arranged between the core portions of two sheets of the adjacent conducting pieces and vice versa.

On the drawings constructional forms of the object of the invention are shown.

Fig. 1 is a longitudinal section through the ignition apparatus with a stationary coil on line E—E of Fig. 2.

Fig. 2 is a plan view of the conducting members and of the ignition coil on line B—B of Fig. 1.

Fig. 3 is a longitudinal section of another constructional form of the ignition apparatus with a stationary coil on line F—F of Fig. 5.

Fig. 4 is a longitudinal section of a further constructional form of the ignition apparatus.

Fig. 5 is a plan view of the conducting pieces and of the pole wheel on line D—D according to the example of Fig. 4.

Fig. 6 is a cross section through the coil core.

In the example of Figs. 1 and 2 a represents the bearing bracket for the drive shaft b of the rotating permanent magnet c which is star shaped with any number of arms. d is the ignition coil and g the laminated core of the latter which has at both ends a cylindric part w and w'. In the case of a permanent magnet with six pole arms the cylindric ends of three L-shaped conducting bars n, o, p abut against the upper cylindric end w of the coil core. The

cylindric ends of the conducting bars r, s, t abut against the lower cylindric end w'. These conducting bars are laminated and fixed in the casting q. Besides they are guided by the ribs y and y' of the covers x and x'. The course of the flux is as follows: Permanent magnet c, conducting bar n, coil core g conducting bar r, and back to permanent magnet c.

With the exception of the air gap between the conducting bars and the permanent magnet there are only two more connections at the ends of the coil core, which however represent a very small reluctance. As the ends w and w' of the core are cylindric and as the ends of the conducting bars are turned out cylindrically also, a very good fit of the conducting bars on the coil core is obtained; thereby the losses of the magnetic flux are reduced to a minimum.

In the example of Fig. 3 the conducting bars n, o, p are U-shaped with arms of different length. The conducting bars r, s, t are Z-shaped, their arms having different lengths also. The shorter arms of the U-shaped conducting bars and the longer arms of the Z-shaped conducting bars form together the coil core in such a way that the shorter arm of each U-shaped conducting sheet is arranged between the longer arms of two Z-shaped conducting sheets and vice versa. The longer arms of the U-shaped conducting bars and the shorter arms of the Z-shaped conducting bars complete the magnetic connection to adjacent arms of the permanent magnet. In the planes in which Z-shaped conducting sheets form part of the coil core, an L-shaped conducting sheet is used between the Z-shaped sheets. In a similar way L-shaped sheets are provided between the Z-shaped sheets where the shorter arms of U-shaped sheets form the core sheets. With the exception of the air gap between the conducting bars and the pole wheel, there are no more air gaps thereby the conditions with respect to the reluctance to the course of the flux are still better than in the case of the example illustrated in Figs. 1 and 2.

This new method of designing the conducting bars and the coil core is not only applicable to magneto electric ignition apparatus with stationary coil and rotating pole wheel, but also to such apparatus with stationary pole wheel and flux distributor or to apparatus with rotating coil systems and stationary permanent magnets.

In the example of Figs. 4 and 5 the conducting bars n, o, p, are L-shaped and their shorter arms abut against the upper cylindric end of the coil core g. At the lower cylindric end of this coil

core a set of sheets with three arms r , s , t are arranged at right angles to the core axis. The ends of the arms of the permanent magnet are bent off parallel to the axis of rotation (compare the parts c' to c'''') and are fitted with lamination sheets A. The course of the flux is similar to that of the first example, i. e.: arm c' of the permanent magnet c , conducting bar n , coil core g , arm r , arm c'' of the permanent magnet and back to the arm c' of the permanent magnet.

As mentioned above, the coil core itself is laminated. As shown in Fig. 6, the single sheets of the lamination are wedge-shaped and mounted together in such a way that they form a round core. In this way the round section of the core is fully utilized and a round hole in the centre is obtained. The drive shaft of the breaker cam and high tension distributor extends through the entire length of this hole. Further the conducting of the flux from the conducting bars of the coil core is favourable as the sections of the conducting bars and of the sheets of the coil core are parallel to each other and do not cross one another as is the case in known designs. Up to now the lamination of the coil core has been made in such a way that a strip of sheet iron was rolled up. A core made in this way often caused short circuits at its ends. In other cases the lamination has been made in such a way that strips of sheet iron of various widths were mounted together in the form of a triangle, but in such designs the round section of the core is not fully utilized.

What I claim is:

1. In a magneto electric ignition apparatus in combination a drive shaft, a rotating permanent magnet, a stationary ignition coil, L-shaped flux conducting bars, one arm of which is at a right angle to the axis of rotation and the end of the said arm being turned out cylindrically, a laminated coil core, both ends of which are cylindric, the sheets of said coil core having wedge-shaped section and being adapted to form a round core with a central round hole, said L-shaped conducting bars being mounted in such a way that they are adapted to abut against the ends of said coil core, end plates for the ignition coil, ribs on said

end plates adapted to keep the sheets of the conducting bars firmly together, a bearing bracket for the drive shaft, a casing for the ignition apparatus in which said conducting bars are fixed.

2. In a magneto electric ignition apparatus in combination a drive shaft, a rotating permanent magnet wheel, the ends of the arms of which are bent off parallel to the axis of rotation, a stationary ignition coil, L-shaped flux conducting bars one arm of which is at a right angle to the axis of rotation and the end of said arm being turned out cylindrically, a laminated coil core, both ends of which are cylindric, said L-shaped conducting bars being mounted in such a way that they are adapted to abut against the end of said coil core, a star-shaped laminated flux conducting member arranged at right angles to the axis of rotation and fixed to the lower end of said coil core, end plates for the ignition coil, ribs on said end plates adapted to keep the sheets of the conducting bars firmly together, a casing for the ignition apparatus in which said conducting bars are fixed.

3. In a magneto electric ignition apparatus in combination a drive shaft, a rotating permanent magnet, a stationary ignition coil, laminated U-shaped flux conducting bars, laminated Z-shaped flux conducting bars, L-shaped sheets, the shorter arm of said U-shaped conducting bars and the longer arm of said Z-shaped conducting bars, being adapted to form the coil core in such a way that each sheet of one type of conducting bar is arranged between two sheets of the adjacent other type conducting bars, and L-shaped sheets being placed each between two sheets of the U-shaped conducting bars in the planes in which portions of the sheets of the Z-shaped conducting bars form parts of the coil core, and between two sheets of the Z-shaped bars in the planes in which portions of the sheets of the U-shaped bars form parts of the coil core, end plates for the ignition coil, ribs on said end plates adapted to keep the sheet of the conducting bars firmly together, a bearing bracket for the drive shaft, a casing for the ignition apparatus in which said conducting bars are fixed.

JAKOB BOHLI.
